CONTROL UNIT FOR LINE CASTING AND
COMPOSING MACHINES

Howard L. Krum, Kenilworth, and Albert H. Reiber, Chicago, Ill., assignors, by mesne assignments, to Teletypesetter Corporation, a corporation of Delaware

Application March 23, 1932, Serial No. 600,606

48 Claims. (Cl. 199—18)

The present invention relates to improvements in line casting and composing machines and more particularly to automatic control mechanisms therefor.

5 Among the objects of this invention one is to provide an automatic control mechanism that may be applied to standard types of line casting machines without changing the manual operating features and retaining the characteristic 10 features peculiar to these machines.

Another object is the provision of an automatic control mechanism that may be applied to a principal machine, such as the present existing line casting machines without materially altering 15 the machines.

Additional objects of the present invention are to provide an automatic control unit compactly fitted to the principal machine to prevent interference with manual operation of the machine 20 and to provide a unit which may be applied to the machine with a minimum of alterations and rebuilding of the machine, thus reducing the cost of the automatic control units and their application to present existing line casting machines.

25 In general the present invention includes a selector mechanism featuring an improved type of selector bar assembly that is positive in operation and sufficiently compact to be disposed beneath the standard keyboard mechanism and to 30 still permit manual operation. The power distribution is conveniently located at one side of the machine and constitutes a small compact mechanism easily accessible for purposes of adjustment or periodic attention. The power for 35 operating the entire unit is derived by means of a pulley and belt connection with the intermediate shaft of the principal machine.

The unit is controlled by a perforated control 40 form which may be prepared by the operation of a machine such as disclosed in Patent No. 2,000,029, granted May 7, 1935, to Edward E. Kleinschmidt et al., and which is fed through a record reading device wherein there is provided a plurality of feeler members each one of which 45 corresponds to a position in the tape that may or may not be provided with a perforation depending upon the particular code combination that is being read. Upon each momentary arrest of the control form the several feelers sense 50 the code combination perforated in the particu-

lar position and upon the next movement the combination is transferred to an intermediate set of storage devices following which a set of code bars are also positioned in accordance with such code combination. The code bars are provided 5 with notches on both top and bottom edges thereof and in this manner they accommodate a double alignment of selectable elements. In the preferred practice of the present invention the selectable elements are alternately and oppositely 10 disposed with respect to each other in scissors-like fashion constituting two rows which are movable toward each other when urged into selected position. For each permutation of the code bars one and only one of these selectable 15 elements may be placed into selected position and when any particular one is thus selected it constitutes an interposition means between an intermittently operated striker bar and a corresponding one of a plurality of keylevers associated with the particular function to be performed. The motion of the common striker element is imparted to the particular keylever as a sharp staccato blow simulating the "touch" of 20 the operator's finger when it is manually operated by means of the keylevers. A cam shaft which is constantly rotated during the normal operation of the record reading device serves to 25 reset the selectable elements and also to actuate the common striker bar and is timed with respect 30 to the operative cycle to perform two complete selective functions for each revolution. It is a noteworthy feature that by virtue of this practice the driving elements need not be moved at a rapid rate since all of the necessary functions 35 are accomplished within a half revolution of the primary driven shaft. While the power take-off mechanism in immediate communication with the principal machine is a constantly rotating 40 shaft the driving mechanism is distributed over two subordinate shafts which are alternatively rotatable as will more clearly appear in the course of the detailed description following hereinafter. One of these subordinate shafts operates 45 that part of the mechanism that has to do with the composing machine while the other subordinate shaft operates that part of the mechanism that transfers the assembled matrices from the composing machine to the mold.

This transfer mechanism, which is referred to 50

in the art as the assembling elevator, is operated in the present system under control of a special code perforation in the control form. During its actuation the operation of the rest of the control unit is suspended but at the conclusion of its performance the operation of the rest of the unit is reinstated automatically. Since there are several possibilities of interference with the complete operation of the elevator and its associated mechanism, frictional disengagement means is provided which, in the event of any such interference, interrupts the mechanical connection between the source of power and the elevator.

A better understanding of the present invention will be obtained from the following description, taken in conjunction with the accompanying drawings wherein,

Fig. 1 is a plan view of a portion of the principal machine illustrated in Fig. 2 showing the control unit in plan elevation.

Fig. 2 is a front elevation of a standard line casting machine having applied thereto an automatic control unit embodying the present invention.

Fig. 3 is an enlarged plan view with parts broken away illustrating the permutation selector mechanism of the control unit.

Fig. 4 is a fragmentary detail front elevation with parts broken away illustrating the selector mechanism and particularly the resilient fingers.

Fig. 5 is a side elevation of the control unit showing the assembler elevator partially in section.

Fig. 12 is a detail sectional view of part of the mechanism illustrated in Fig. 11 in operated position.

Fig. 13 is a detail sectional view similar to Fig. 12 illustrating the same mechanism under a different condition of operation.

Fig. 14 is a detail sectional view taken on line 14—14 of Fig. 1.

Fig. 15 is a detail sectional view taken on line 15—15 of Fig. 1 illustrating the power take-off clutch control mechanism.

Fig. 16 is a longitudinal cross-sectional view through the record reader mechanism and associated parts.

Fig. 17 is a detail perspective view of the elevator selector bar blocking mechanism.

Fig. 18 is a detail sectional view taken approximately on line 18—18 of Fig. 3 and illustrates the cam actuator of the common striker.

Fig. 19 is a detail perspective view of several matrices in two-position assembled relation.

Referring now to the accompanying drawings 75 in which like reference characters designate

similar parts throughout, Fig. 1 illustrates generally the application of the present device to a line casting machine.

Framework

In its preferred form the present invention comprises a unitary structure that is almost entirely supported on the main or principal framework 21, best indicated in Fig. 6. This framework is mounted beneath a standard keyboard base casting 23, Fig. 6, is modified slightly by re-locating a cross-support rib 24 rearwardly so as to admit of enough clearance between it and the elevator operating shaft 25 for passing the off-set portions 26 of the levers 27 therebetween. While in the case of the majority of the weight bars 59 there is provided not only a manually operated keylever 57 but also an independent automatically operated lever 27, it will be noted that this is not true in the case of those characters whose manually operated keylevers are situated in the lower two of the six horizontal rows of keylevers, Fig. 7. In the case of these two rows of keylevers, instead of providing separate automatically operated levers 27, each keylever 57 has been modified by the addition thereto of an off-set portion 26 generally similar to the corresponding portions 26 of the keylevers 27, but in this case integrally formed with the manually operated keylevers. A pair of studs 28 are provided, one on each side of the base casting 23 for supporting the lug portions 29 while the elevator operating shaft sleeves 30 support the foremost lugs 31. The major portion of the framework extends under the entire keyboard and supports among other things the permutation bars 32 and the selectable interposition bars 33. The framework comprises two side frames 34 and 35 which by means of their portions 29 and 31 are adapted to receive studs 28 and elevator shaft sleeves 30 and thereby be supported and in turn support the rest of the unit mechanism.

Driving train

A suitable driving pulley 36 is attached to the intermediate shaft 37 of the principal machine and drives through the medium of a pulley belt 38, a driven pulley wheel 39, and a constantly rotating shaft 41 better illustrated in Figs. 1 and 2, which carries securely mounted to it two worm gears 42 and 43. Worm gear 42 drives a worm wheel 44, Fig. 14, which is freely mounted on a shaft 45 suitably journaled in bearings 46 that comprise part of the framework 21. Worm gear 43 engages a worm wheel 47 in the same manner as its associate driving worm 42 except that being of somewhat smaller diameter and bearing a correspondingly greater ratio to its driven wheel 47 it imparts a correspondingly slower motion to its driven shaft 48 than is imparted to the driven shaft 45. Each of the shafts 45 and 48 is coupled with its respective gear 44 and 47 through spring loaded tooth clutches 49 and 51 preferably of similar construction.

Shaft 45 carries three cams that operate the record reader mechanism 54 and will be referred to hereinafter as the record reader shaft, while additionally it also carries a driving gear 52 (see Fig. 1) that operates a cam shaft 53. Shaft 48 carries a cam 55 for operating the elevator mech-

anism and another cam 56 for disengaging its own driving connection and for controlling the driving connection to the record reader shaft 45 at the conclusion of each cycle of its own operation, and will be referred to hereinafter as the elevator cam shaft.

Keyboard control

Referring now to Fig. 7, wherein a typical cross-section through the selector and matrix release mechanisms is indicated, attention is directed to the standard keyboard construction in particular contemplation of which this structure has been designed. Keylevers 57 pivoted on shafts 58 are suitably articulated to move members or weights 59 as at 61 admitting of considerable lost motion at their several points of articulation by virtue of excess clearance 62. A particular "touch" is obtained by providing a uniform leverage ratio in all of the keylevers, although, as is readily seen, each horizontal row proceeding downwardly is progressively longer than its preceding one. The weights 59 are provided with several notches 62 so as to be adaptable to standard replacement in connection with other of the several keylevers. Additional levers 27 pivoted at 64 are mounted for engagement with the lowermost notch 62 of certain of the several weights 59 and are provided with offset extensions 26 that protrude through a panel 63 of the keyboard. Thus, it will be seen that as to the release of matrices controlled by keylevers in the upper four rows, Fig. 7, either the manual control levers 57 or the automatic control levers 35 27 may be operated independently and that in so doing the other or unoperated of the two remains inert and does not in any way enter into motion either associatively or collaterally, but as to the release of matrices controlled by the keylevers in the lower two rows a single lever is utilized for operation both manually and automatically.

An alignment of bell crank levers 65 fulcrumed on a common shaft 66 is disposed to overlap the aforementioned extensions 26 so as to engage them when rotated clockwise and against the action of individual springs 67. The vertical arms 68 of the bell cranks 65 register opposite certain ones of a corresponding plurality of selector bars 33 which, as will be noted from Fig. 7, are disposed in opposite symmetrical alignments and resemble a scissors-like formation by reason of their peculiar shape. Both alignments of bars 33 are primarily supported upon a common shaft 69 about which they are urged towards each other under influence of individual springs 71. Offset portions 72 of these bars 33 are normally spaced apart, while intervening the two alignments the set of permutation bars 32 and rotating spreader cam shaft 53 are positioned for performing the selective action.

Selector mechanism

Cam shaft 53 is provided with two longitudinal cam surfaces 73 and in rotating counterclockwise, during each half revolution thereof, the shaft 53 tends to spread the selector bars 33 and then to permit them to approach each other. The surfaces or apices 73, while at rest and holding apart the selector bars 33, cause the latter to clear the edges of the permutation bars 32 as indicated in Fig. 7, but immediately after leaving this position, and during rotation as indicated in Fig. 8, the several bars 33 are permitted to approach each other and to contact the edges of

the set of permutation bars 32 and for each condition of the several bars 32, an individual alignment of notches 74 (Fig. 9) is afforded into which the adjacent selector bar 33 is permitted to drop. As may be seen in Figs. 7 and 8 notches 70 located in the portions 72 of bars 33 are provided adjacent the spreader cam shaft 53, so as to permit a sudden drop by a selected bar 33 when the cam 73 passes from under it. This practice allows greater time for the selector bars 33 to be disposed in position for operation and also hastens its presentment thereinto relative to an operative cycle. Upon selection the foremost portion 75 of the bar 33 either of the upper alignment or of the lower one, as the case may be, presents itself so that its shoulder 76 may be engaged by a striker bar 77. When the striker bar 77 moves leftwardly, as viewed in Fig. 7, it engages the shoulder 76 and carries the selector bar 33 bodily with a sharp staccato motion, driving it against the lever arm 68 of its particular bell crank lever 65. The movement of the several selector bars 33 is defined by elongated slots 78 which straddle the common shaft 69.

Particular attention is now directed to the bell crank shaft 66 as well as the recessed portion 79 (Fig. 8) of the several bell cranks 65 which are seated upon the shaft 66. The normal operative movement of the manual keylevers 57 is relatively slight and correspondingly the movement of the automatic control levers 27 needs also be but slight, yet in the matter of regulating the stroke of the automatic control unit, no critical adjustment is required, since any surplus movement that is imparted to the bell cranks 65 and that may not be fully received by the special levers 27, but may be resisted by them, is dissipated in displacing its bell crank 65 outwardly and upwardly of its fulcrum seat 79 as indicated in Fig. 8. Not only does this provide a commercially feasible means for adjusting a large plurality of closely positioned and critically operative members, but also it provides a means whereby in the event of any resistance, whatever, on the part of any particular keylever 27 the positive blow originating from the common actuator 77 will not damage any of the components in the described mechanical train, but may be harmlessly absorbed by the yielding movement of the bell crank levers 65. After completing its function, each selector bar 33 is returned to its normal position primarily through the influence of its individual spring 71, but augmented in part by the spring 67 of its associated resilient bell crank lever 65.

Record reader

Of the several code bars 32 in the present embodiment, six of them are positioned in each cycle of operation through the agency of a record reader mechanism 54, while a seventh one 81 is positioned by a special structure subordinated to the previous six bars 32 as will be described hereinafter. Referring now to Fig. 16, the right hand portions of the selector bars 32 will be seen connected to connecting bars 82 which are in turn supported in suitable trackways 83 for longitudinal and parallel movement. Ends 84 of levers 82 opposite the aforementioned articulation to the selector bars 32 are provided with elongated slots 85 into which are received disc portions 86 of T-shaped transfer levers 87. Levers 87 are also provided with arms 88 (Fig. 9) which are terminated with abutment lugs 89 and 91.

A corresponding set of six feeler levers 92 is pivotally supported directly above the T-shaped

5

levers 87 and their lowermost portions (Figs. 9 and 16) are of such proportions that when either of two shoulders 93 or 94 is brought into registration with its associated actuating lug 89 or 91 the other of the shoulders 93 or 94 just clears its associated lug. Feeler levers 92 are provided with an intermediate orifice 95 having sufficient clearance with respect to a fixed rod 96 positioned thereinto so as to permit of a slight reciprocative motion by the levers 92 as best suggested by Fig. 16. In its limit of movement each feeler lever 92 may be positioned so that one or another of its shoulders 93 or 94 is brought into registration with its associated abutment lug 89 or 91. The several T-levers 87 are supported on a common shaft 97 which in turn is carried by one arm of a bell crank lever 98 pivoted at 99, the short arm of which abuts a short arm of another bell crank lever also pivoted at 99, the other end of which carries a roller 101 spring urged to follow the peripheral surface of a cam 102 secured to the shaft 45 described above. The cam 102 has a gradually ebbing apex and when it is rotated together with its shaft 45 it imparts a regular and reciprocating motion to the lever 98 and its associated T-levers 87.

The feeler levers 92, so called because of their function in sensing the attributes of a transverse line of tape perforations, are provided with arms 103 which carry feeler pins 104 and are also provided with projections 105 serving to be engaged by a bail 106 for periodically withdrawing the levers 92 in accordance with each successive reading of the record tape. The bail 106 moves as part of a bell crank structure 107 which also is actuated by the shaft 45 through a cam 108 and roller 109 engagement similar to the one described in connection with lever 98. Thus, it will be seen that in accordance with the timed action of bell crank 107 and lever 98 the set of feelers 92 will first be permitted to rotate counterclockwise during which time those of them whose pins 104 are not blocked by the record tape 111, Fig. 9, but which are brought into registration with a perforation thereof, will be permitted to rotate until their respective shoulders 94 register opposite the abutment lugs 91 while the others which are not so permitted to do will remain in position with their shoulders 93 in registration opposite 50 the abutment lugs 89.

Immediately following this condition, the cam 102 moving lever 98 counterclockwise forces the several T-levers 87 into engagement with their respective feeler levers 92 and, depending upon which of the two positions the feeler levers happen to assume, T-levers 87 will be correspondingly positioned and will impart a similar position to their associated bars 82. In this manner the combination of perforations present 60 in each transverse alignment in the tape is translated simultaneously to the six code bars 82. Following each such translation the tape 111 is stepped forward until another transverse alignment of perforations is brought into registration with the feeler pins 104. This stepping is accomplished by a pawl 112 and ratchet wheel 113, better illustrated in Fig. 10. The pawl 112 is carried by a reciprocating lever 116 which receives its motion from a cam 115 carried by the driven shaft 45 and spring 116. The ratchet wheel 113 is secured to a shaft 117 which also carries a sprocket wheel 118 having minute teeth 119 especially adapted to register with the central perforations 121 of the control tape 111 in accordance with the well known practice. In this man-

ner the single shaft 45 operates all of the mechanical agencies that control the record reader mechanism.

Particular attention is directed to the fact that while the several feeler levers 92 are brought back to a normal or starting position at some definite point in each cycle of operation, yet the transfer levers 87 and their articulated slide bars 82 are not so restored, but may be set in conformity with a new code combination regardless of their previous position. This practice permits of an overlap in the operation of the two sets of levers and allows the code bars 82 maximum time of rest during each cycle of operation.

In addition to carrying the record reader operating cams 102, 108 and 115, shaft 45 also carries worm 52 which in cooperation with wheel 122, Fig. 1, imparts rotation to the spreader cam shaft 53 described above, thus tying up completely the several agencies of the selector mechanism under control of a single shaft, namely, the record reader shaft 45. Since driving worm 52, in thus operating the spreader cam 53 and its associated mechanisms, bears a definite and somewhat critical timed relationship to cams 102, 108 and 115, its angular relationship thereto is made positive by having provided at the abutting hub portions of collar 123 and worm 52 fine radial serrations 124, which when worm 52 is drawn up against collar 123 by means of a nut 125 and thereat locked in position by another nut 126, serves to positively prevent slippage between the two members. In assembling, this construction affords a convenience of permitting the two controlled mechanisms, the spreader cam 53 and the transfer bail 97, to be set at a known relative position after which it is necessary but to move the two timed means, cams 102, 108 and 115 and worm 52, into their obvious positions.

Release mechanism overlap

Referring now particularly to Figs. 3 and 7, attention is directed to the matrix release mechanism, the selector bars 32, as well as to the permutation bars 32 and 34. The operation of any of the weights 58, either through the medium of the manually controlled key lever 57 or through the automatically controlled lever 27, results in releasing a corresponding one of a plurality of time delay mechanisms. This is accomplished by rotating trigger 127 counterclockwise until it ceases to support its cam yoke 128 whereupon the latter member drops until the peripheral teeth 129 of cam 131, which is pivoted between the tines of said yoke, engage a continuously rotating rubber roller 132. The engagement between the teeth 129 and the roller 132 imparts a clockwise motion to the cam 131 which, on account of its eccentricity raises yoke 128 until its remote end 133 abutting a release reed 134 imparts a timed stroke through the matrix release mechanism, illustrated generally at 135, whereupon it is again supported by the trigger 127 pending another release movement.

The purpose of the timed release mechanism, as is generally known, is to permit of sufficient time in the magazine trip 135 without having to expend the same amount of time in depressing a control key 57 or 27. The imperativeness of such an element of delay is made of principal importance in view of the fact that the matrices are released and allowed to gravitate into assembled relation, for without such and, particularly under the speed of automatic control, a direct

release means might be actuated and be restored to normal position before its matrix has had time to move from its magazine.

5 *Special function bars*

One of these overlap mechanisms is provided with each of the levers 27 whose function it is to release a matrix 136 from the magazine 137. Certain of the keylevers are adapted to be actuated for the performance of special functions wherein there is no need for the intervention of a time delay element. Each of these functions is accordingly provided with a lever 27 as well as an individual selector bar 33. In contradistinction with the matrix selector bars the special function bars are provided with integral lugs 138, Figs. 3, 9, and 17, each of which is adapted to engage associated mechanism for the performance of some particular function as will be 20 explained.

Selector bars 139 and 141 acting cooperatively determine the positioning of the seventh code bar 81 in the following manner. When the selector bar 139 upon being selected is moved forward, 25 its lip or lug 138 engages one arm of a bell crank 142, Fig. 3, rotating it clockwise and imparting a similar motion to trigger 143 through the medium of a connecting link 144. This movement of trigger 143 liberates lever 145, with which are 30 integrally associated arms 151 and 152, permitting it to respond to the urge of its spring 146 and to attempt to shift permutation bar 81 leftwardly through engagement arm 151 with projection 149 of bar 81. In the preferred embodiment of the lever system for shifting the permutation bar 81, a slight clearance is provided between the end of lever arm 151 and the projection 149 of bar 81 when lever arm 145 is retained by the shoulder 155 of latch 143. The 35 purpose of such clearance is that, if for any reason the permutation bar is not shifted by the spring 147 immediately upon actuation of the latch 143, the end 154 of the lever arm 145 shall be released from the shoulder 155 and shall not 40 be restored to retained relation therewith if the latch 143 returns to unoperated position before the bar 81 is shifted. The clearance permits sufficient rotation of the lever arm 151 and associated arm 145 to assure that upon restoration 45 of the latch 143, the end 154 of lever arm 145 shall be below shoulder 155.

In the preferred construction of the bar 81 it is without blocking projections in the portions immediately adjacent to the selector bars 55 139 and 141, so that there are no narrow, confining code notches in bar 81 into which those selector bars drop, upon selection, and it follows from this that the seventh code bar 81 does not block the selection of either of the selectable bars 60 139 and 141 in either of its selecting positions. However, the action of the springs 71 upon selectable bars 33 is such that it causes the bars 65 33 to seek engagement with the edges of the code bars 32 and 81 and those selectable bars which encounter code projections rest thereon in frictional engagement. The force exerted by the energy stored in the spring 147 for shifting the 70 shift bar 81 may be ineffective until the frictional engagement between the selectable bars and the shift bar is relieved. Such relief occurs once in each cycle of operation of the control mechanism by reason of the previously described action of the spreader cam 73. In this way the 75 shift bar 81 may be restrained from movement by the spring-urged lever arm 151 upon actuation

of the latch 143, and its shifting may be delayed until the spreader cam 73 has eliminated frictional restraint upon the shift bar 81.

In like manner, the selection of cooperative bar 141 causes the shifting of permutation bar 81 in the opposite direction. This is accomplished by a similar lug 138 formed integrally with bar 141 which, upon its selection, engages one arm 152 of the lever 145, moving it counterclockwise about the pivot 153, expanding spring 147, and again latching projection 154 behind shoulder 155 of trigger 143. A third class lever 148 connected to the opposite end of spring 147 is urged thereby to shift bar 81 rightwardly as soon as it is allowed to do so by the relief of frictional restraint upon operation of spreader cam 73. Here, too, as in the first case, the actual shifting of permutation bar 81 awaits the relief of frictional restraint and is effectuated through the instrumentality of the loaded spring 147. Thus 20 is provided a shifting means for a seventh permutation bar, doubling the permutative possibilities at the expense of two of the sixty-four simple permutations afforded by the six original permutation bars. 25

As already described the six permutation bars 32 are each correspondingly positioned in accordance with the occurrence or absence of a perforation in its portion of the control form. By reason of the two possible conditions of each bar 32 there are afforded sixty-four simple permutations by the aggregate positions of the six bars. But since the total requirement of a line casting machine standard keyboard is in itself ninety-one operations there being ninety-one 35 keys, and since with the additional special functions the requirement approaches one hundred and fifteen the simple permutations of six bars are not enough, so the seventh bar 81 is added to increase the permutations. 40

The seventh bar 81 is in itself the simple addition of another bar similar to the six already provided, however, since it is not desirable to increase or change the standard perforated control form this bar 81 is positioned by operation 45 of one or the other of two selector bars as already described which in turn are selected by the six original bars 32. Thus, while two permutations are consumed in shifting the seventh bar 81 the total resulting permutations are increased to 50 one hundred and twenty-six. 55

Special selector bar 156 is adapted to be selected upon the reception of an elevator operating signal. Its movement forward engages one arm 157 of a T-shaped lever 158 thereby rotating it counterclockwise about its pivot 159, Fig. 9, and against the action of its spring 161. When so rotated another arm 162 of lever 158 pulls connecting link 163 rocking bell crank 164 clockwise (Fig. 15), which by means of its arm 165 forces 60 disengagement cam lever 166 into effective position for withdrawing driven member 167 of clutch 49 and arresting the record reader shaft 45. The other arm 168 of lever 158 is connected to a bar 169 which during the described rotation is thrust 65 rightwardly (Fig. 9) until its offset portion 171 is latched behind shoulder 172 of spring urged lever 173. An upstanding lug 174 of bar 169 is pivoted to one end of floating lever 175 through which it moves said lever during its own movement. 70

A fourth selector bar 160 located at the extreme left position of the several selector bars 33, Fig. 3, is adapted to engage one arm of a first class lever 170, the other arm of which actuates a rail 75

shift mechanism, to be referred to hereinafter. Thus, are described generally the location and operation of the several function selector bars, (so called in contradistinction with the matrix 5 selecting bars) in order that they may be readily associated with their particular controlled mechanism when the latter are described hereinafter.

Assembler rail shift

- 10 The matrices upon being released from their several channels 176 in the magazine 137, Fig. 2, fall into one or another of a plurality of chutes and from there onto an inclined conveyor belt 177 and thence in turn they are collected upon an assembling block 178. This block 178 is provided with a pair of fixed lower rails 179 and a displaceable upper rail 181, also illustrated in Fig. 19. When the upper rail 181 is in its dotted position, Fig. 5, subsequently received matrices assume 15 a position 182, but when this rail 181 is withdrawn as illustrated in solid lines subsequently received matrices will be permitted to drop completely down so as to assume the position 183 illustrated in dotted lines.
- 20 25 In accordance with the usual practice each matrix is provided with two molding impressions 184 and 185 as illustrated in Fig. 19 and, depending upon which of the two positions that the particular matrix assumes upon the assembling 30 block, one or another of the two molding impressions will register opposite the mold chamber in casting the particular slug. The movable rail 181 is articulated to a bell crank lever 186 capable of limited motion and critically adjustable through 35 the medium of stop screws 187—187. A connecting link 188, pivoted to the bell crank 186 at one arm thereof, is connected to a spring loaded lever 189 pivoted at 191 which has at the opposite end thereof a shouldered portion 192. A trigger 193 40 affords trip engagement with said shouldered portion 192 and has at one end thereof an upstanding part 194 suitable for manual manipulation, while at the other end 195 thereof it is positioned for release control by the first class lever 170 45 described above.

Upon the actuation of the selector bar 160 which in turn moves lever 179 this trigger 193 is moved permitting lever 189 to yield in accordance with the urge of spring 196 and to present 50 the shiftable rail 181 in its effective position (dotted lines). This condition may also be attained manually through the operator's releasing trigger 193 by taking hold of the upstanding portion 194. In this manner it is possible to assemble 55 part of the line with the matrices in their down position and part with the matrices in their up position either under manual or automatic control.

Elevator control

- 60 When a sufficient number of matrices has been accumulated on the assembling block 178 with which a complete line may be molded, an elevator operating signal is sent through the record reader mechanism 54 which causes the selection 65 of elevator operating bar 156 and the arresting of record reader shaft 45 stopping the feeding of the control form as already described. This action rotates T-shaped lever 158 moving link 70 163 leftwardly and slide 169 rightwardly. Since link 163 is connected to clutch release lever 166 its movement leftwardly, as viewed in Figs. 9 and 15, presents clutch release lever 166 into position 75 for engagement with beveled lug 197 (Fig. 14) carried on the driven portion 167 of spring loaded

clutch 49. The motion of record reader shaft 45 continues until lug 197 comes into engagement with lever 166 whereupon it enters the orifice 198, engaging with its beveled edge 199 the corresponding inclined surface 201 of lever 166 and bringing shaft 45 to a stop. In so doing, lug 197, Fig. 15, as well as driven member 167 are forced out of engagement with respect to driving clutch member 202 and are temporarily so held by means of a detent lever 203 whereby the roller carried thereon is spring urged to fall behind shoulder 204 of disc 205 and to thereby further force driven member 167 rotationally and through cam lug 197 axially out of engagement with respect to driving member 202, by reason of the slight frictional relationship between the driven member 167 and the shaft 45 which is preferably sufficient to maintain said member 167 well away from any engagement therebetween. In this manner the usual singing noises, which ordinarily exist in spring loaded clutches that are equipped with inclined surface disengagement means, are abated.

Slide bar 169 in moving rightwardly is latched by shoulder 172 of member 173 and in association with T-lever 158, imparts a similar motion to one end of floating lever 175, Fig. 9, to which it is connected at 206. The opposite end of floating lever 175 is straddled by a yoke 207 which terminates the connecting link 213, whose opposite end is articulated to delivery slide control lever 208 located adjacent the delivery slide arm 211 and supported so as to be maintained in its extreme clockwise position and against the action of a spring 209, Fig. 2, during the time that the delivery slide arm is in its right hand or normal position. When the slide arm is operated, however, as is the case following a movement of elevator 212, it rocks leftwardly and permits lever 208 to respond to the urge of its spring 209 and rotate counterclockwise, thereby thrusting the connecting link 213 to the left and shifting one end 214 of the floating lever 175 and in this manner contributing in part to the resulting movement of the central portion 215 thereof so that the latter may depart from the depending arm 216 of bell crank 217. The other arm of bell crank 217 is provided with a shouldered extremity 218 adapted to hold clutch release lever 219 in its effective position for disengaging the elevator power shaft 48. When, however, bell crank 217 is moved by the central portion 215 of floating lever 175, which occurrence can happen only upon the combined movement of connecting link 213 and bar 169, the foremost portion 218 of bell crank 217 is raised sufficiently to permit spring 221 (Fig. 15) of clutch 219 to move it out of its effective position, thereby releasing driven member 222 of the elevator clutch 51 and establishing power connection to shaft 48.

The actuation of floating lever 175 is indicative of the following two predetermined conditions; first, that an elevator signal has been received, and second, that the delivery slide arm 211 is in its extreme right hand position which in turn indicates that the elevator 212 has been properly returned in consequence of the preceding elevator signal. Thus, it will be understood that the elevator operating shaft 48, being controlled through bell crank 217 by floating lever 175, may not be actuated until both of the aforementioned conditions are first established.

Where after a previous operation the elevator has been properly restored and thereafter another elevator operating signal is received,

driving power is imparted through gear 47 and driving clutch member 223, driven clutch member 222 to the shaft 48. The continued rotation of shaft 48 carrying with it elevator cam 55 raises elevator shaft arm 224, Fig. 11, by reason of its engagement with follower roller 225. The normal rotation of cam 55 operates to move elevator shaft 25 through the medium of arm 224 and auxiliary arm 226, Fig. 12, which contains a spring loaded detent 227. The foremost portion of detent 227 is provided with a V-shaped nose 228, which during normal conditions is received into a corresponding notch 229, Fig. 13, in segment member 231. Upon the contingency of any undue resistance to the motion imparted by cam 55, such as, for example, a disorder in the elevator mechanism or blocking thereof, spring loaded detent 227 will yield, come out of engagement with notch 229 and ride in a trackway 232 of segment 231. The frictional engagement between detent 227 and its associated segment member 231 may be suitably controlled by varying the tension of spring 233 in accordance with a desirable factor of safety at which said detent is to yield.

Secured to shaft 25 is also a handle 234 for manually operating the elevator raising mechanism. As indicated in Fig. 12, when the cam 55 is in operated position manually controllable handle 234 is normally allowed to assume a position corresponding relatively to it. However, in the event of any interference with the movement of handle 234, such as, for example, an operator seated before the control board having his knee under it, will cause the motion to be received entirely by thumb lever 235 by reason of the projection 236 of arm 234 engaging a protruding pin 237 of thumb lever 235. Thus, also, in the event of any inadvertent blocking of the handle 234 by an operator, no injuries can occur to him, such as might occur otherwise.

A finger 238, Fig. 9, carried by elevator operating arm 224 is adapted to overlie an extended portion 239 of a release bail 241, normally spring urged, as at 242, to engage; by means of its arm 223, the upper extremity of clutch release lever 166. During the rise of arm 224 when the elevator mechanism is first set in motion, finger 238 releases bail 241 so that the clutch lever 166 is thereby held in operative position for disengaging the clutch 49 of the record reader control shaft 45. In the course of rotation, roller 225 rides onto the apex of cam 55 and during the extended dwell thereof maintains the elevator 212 in its upward position, but following this, the elevator having delivered its load of matrices to the delivery slide, roller 225 rides down from the apex portion of cam 55 and again assumes a normal position, as illustrated in Figs. 9 and 16. Correspondingly, finger 238 again engages projection 239 of bail 241, thereby permitting clutch release lever 166 to be moved out of operative position and at once releasing the driven member 167 to establish driving connection to shaft 45.

During the elevator operating cycle and while shaft 48 is rotating, T-lever 158 is maintained for a short duration in its extreme counterclockwise position by means of the off-set portion 171 of lever 169 engaging the shoulder 172 of a trigger member 173. Shortly after shaft 48 is started into rotation, trigger release cam 56 engages side arm 244 of trigger 173 depressing it sufficiently to permit bar 169 to override the shoulder portion 172, thereby freeing T-lever 158, and allowing it in response to spring 161, to again assume its

clockwise position. In thus moving lever 158, spring 161 also disengages release lever 166 through the medium of link 163, while at the same time floating lever 175 is partially restored to normalcy through its connection 236 with bar 169 thereby permitting bell crank 217 to again present itself in position for holding release lever 219 in effective position. Shaft 48 then completes its cycle coming to rest again when its beveled lug (identical with that 197 of clutch 49) reenters the opening of lever 219.

As will be noted from Fig. 15 clutch release lever 219 is normally spring urged out of position to engage the lug of driven member 222 of the elevator power shaft 48, so that to restore it a positive means is employed consisting of a bell crank lever 245, one arm of which carries a follower roller 246 disposed to ride the periphery of clutch cam 247. This cam is similar to the one 205 of the record reader shaft 45 and also functions in the same capacity with respect to its associated clutch members as does the latter. Its operation as a means for effecting the disengagement of elevator power shaft clutch 48 is collateral to its function as a part of the clutch 25 detent mechanism and since the objects of its two functions are merely sequential in each cycle of operation the same cam is made to serve both purposes. The other arm of bell crank 245 engages lever 219 when the apex of cam 247 opposes roller 246 and forces it, against the tendencies of its spring 221, to reengage the revolving lug of driven member 222. Thus, in effect, the several components of this mechanism constitute a single revolution clutch since they come into play spontaneously during each complete rotation of shaft 48. When the elevator shaft 48 is actuated it completes one revolution during which time it performs all of its functions including the holding of record reader shaft 45 in arrested position and thereafter releasing it and disengaging itself. Its operation is inevitable though interference is had with the operation of the elevator itself or in the event of any other irregularities subsequent to the elevator cam 55 in the operating train. The movement of link 163 rightwardly, Fig. 9, pursuant to its release by latch 173 does not release shaft 45 for rotation unless the elevator 212 has been returned and ready to receive a new line of matrices in its assembly block 178. This prerequisite is manifest when upon the descent of the elevator finger 238 engages projection 239 rotating bell crank 241 and withdrawing arm 243 from its blocking position behind lever 166 after which the latter member in response to spring 272 assumes its ineffective position.

Common actuator

Worm 52 secured to cam shaft 45, Fig. 1, is adapted to engage a gear 122 which is secured to an extended portion of cam shaft 53 and is thereby adapted to impart rotary motion to said cam shaft in timed relation to the several other selector mechanism functions. However, since cam shaft 53 is provided with two apices 73 oppositely aligned, worm 52 bears such ratio to its companion gear 122 as to permit two cycles of operation to shaft 45 while cam shaft 53 is making but one. At the opposite extremities of shaft 53, Fig. 3, just inside the side frames 34 and 35 are located striker cams 248 and 249, Fig. 18.

These cams 248 and 249 are symmetrically positioned with respect to each other and are adapted to engage follower rollers 251 carried upon bell

cranks 252. The intermediate portions of each bell crank 252 are provided with slots 253 into which are adapted to slide end rollers 254 of striker bar 77. Springs 255 urge rollers 254 constantly against the peripheral cam surfaces of cams 248 and 249 and in cooperation with the abrupt apices 256 thereof serve to impart a sharp staccato motion to the striker bar 77, thereby simulating a manual control operator's touch as 10 mentioned above.

Premature elevator signal interceptor

It has been mentioned that the preferred practice of the present invention entails adherence 15 to the use of standard perforated control forms of the six unit type. This control tape is sometimes also used for controlling other automatic devices wherein the details of operation and control may vary specifically from that which is 20 requisite in the instant case. Accordingly, means are herewith disclosed for reconciling to the present system of operation certain practices which are essentially foreign to it. So long as elevator operating signals are properly spaced apart, with 25 sufficient numbers of matrix-operating signals therebetween, there will be no need for the intervention of the mechanism about to be described, but in the event one of these signals follows too closely upon its preceding one this mechanism 30 operates to prevent the subsequent signal from becoming effective. The practice of perforating two of these signals adjacently is sometimes had for purposes of controlling other mechanisms with the same tape, which mechanisms 35 require the practice for their peculiar attributes.

Referring to Figs. 2 and 17 attention is directed to the delivery slide operating arm 211 of the principal machine. When matrices are assembled in the block 178 they intervene an up-right 40 lug 258 of slide 257 and a star wheel (not shown) and in so doing move the assembly slide 257 leftwardly, Fig. 2. Until enough matrices are thus assembled for moving it clear thereof, the right end of the slide 257 engages one arm 259 of a bell 45 crank 259 maintaining it in its clockwise extremity against the influence of spring 261. The other arm 262 of bell crank 259 is connected through link 263 to a cradle 264 which carries a blocking arm 265 normally disposed to overlie the 50 end portion of an extension 266 formed integrally with elevator selector bar 156.

In this position, when an insufficient number of matrices are assembled and an elevator signal is received, the blocking of extension 266 by arm 55 265 prevents the selection of bar 156 since it cannot then respond to the urge of its spring 71 though an alignment of code notches 74 is presented under it by the permutation bars 32. As soon, however, as sufficient matrices are assembled to permit spring 261 to effect a movement of cradle 264; that is, by the moving of slide 257 out of range of bell crank arm 259, a subsequent elevator signal may be fully effective and may cause the selective operation of bar 156 to actuate the 60 elevator. As illustrated the proportions are such that but few matrices will suffice to condition bar 156 to be selectable, it being understood that changes to vary this prerequisite are only a matter of mechanical expediency.

70

Control switch

In order to use a line casting machine, equipped with an automatic control unit such as the one herein described, for simple manual composition 75 means have been provided for conveniently

shunting out the unit. A manual control lever 267 is secured to a horizontal shaft 268, Figs. 2, 14, and 15, the rearward end of which carries a cam 269 in cooperative alignment with an extended portion 271 of lever arm 165 which in turn acts upon the disengagement lever 166 of clutch 49, as already described. In solid lines in Fig. 15 is shown the cam 269 maintaining lever 164 in effective position to stop shaft 45 thereby arresting the record reader and discontinuing all activity in the unit beyond the constantly rotating shaft 41 and its associated driven gears 44 and 47. Under this condition the keyboard 22 may be controlled manually with no interference to or on the part of the unit mechanism. In its dotted line position, however, cam 269 clears projection 271 of lever 164 permitting spring 272 to move lever 166 out of engagement with clutch member 167 thereby restoring the motion to record reader shaft 45 and rendering the unit operative. 10 15 20 25

Operation

In the operation of the present device, a perforated control tape 111 is previously prepared, as described in the reference above, and is inserted into the record reader mechanism, generally indicated at 34, where it progresses in a step by step manner under the actuation of an intermittent motion shaft 117 which is moved by pawl 112 and ratchet 113 engagement, as described. During the momentary rest period in the progress of the tape the several feelers 92 are permitted to rotate counterclockwise as viewed in Fig. 16, during which time those of them whose pins 104 encounter perforations in the tape 111 continue to so rotate until their abutment shoulders 94 register opposite the right hand lugs 91 of T-levers 87 while those whose feeler pins 104 do not encounter perforations are blocked in position with their shoulders 93 opposite their lugs 89. Following this and before the several feelers are collectively reset by bail 106, Fig. 16, the transfer levers 87 are bodily reciprocated by cam 102 and in so doing a setting of the several feeler levers is correspondingly translated to the transfer lever 87. While the set of levers 87 rock in a direction transverse to that of their associated bars 82, nevertheless they continue to engage said bars by reason of the elongated slots 85 which are ample to accommodate the transfer lever discs 86 throughout their entire motion. The positioning of levers 87 simultaneously effects the corresponding positioning of bars 82 as well as that of their associated code bars 32. 30 35 40 45 50 55 60 65 70 75

For each permutation of positions in which said code bars 32 are set, one of the plurality of selector bars 33 is dropped into a transverse alignment of notches 74 and is permitted to assume a position substantially as that indicated in Fig. 8, whereupon the striker 77 engaging shoulder 36 moves the entire bar 33 forwardly. Where the particular bar selected happens to be one of the few function bars particularly described above, a matrix is not thereafter released, but instead a preparatory operation is consummated depending upon which of these bars it happens to be. When, however, a matrix selector bar is thus selected to be moved forward by the striker bar 77, it rotates the resilient finger 65 corresponding to it, which in turn actuates a particular one of the plurality of special key levers 27, thereby releasing the associated time delay mechanism and subsequently releasing a particular matrix 136. The matrices thus re- 75

leased are received through their respective chutes and the conveyor belt 177 onto an assembling block 178. In being positioned on the assembling block the matrices may be supported 5 in either of two positions as indicated in Fig. 5, in dotted lines depending upon the presentment or withdrawal of the upper rail 181. The control of this rail 181 lies within the province of a special selector bar 160 responsive to a special 10 conditioning signal.

When a sufficient number of matrices are accumulated upon the assembling block 178 to comprise a complete casting line, an elevator signal is thereafter received. This signal operates 15 to select bar 156 provided, however, that sufficient matrices are in position on the assembling block. When bar 156 is permitted to drop into selective position for moving forward as described above it causes the counterclockwise rotation of 20 T-lever 158, moves bar 169 rightwardly until its offset portion 171 is latched behind shoulder 172 and causes the arrest of record reader shaft 45. Although the record reader shaft 45 has been 25 thus arrested the elevator power shaft 48 is not thereby started unless, too, the delivery slide arm 211 is in its normal position so that through rod 213 and yoke 207 the end 214 of floating lever 175 is in its rightward position. While the elevator mechanism is set in motion the record reading mechanism is stopped, pending its return at 30 the conclusion of the completed matrix delivering operation. After elevator power shaft 48 has completed its cycle and has stopped itself at the conclusion thereof, record reader shaft 45 is 35 immediately started into operation by the rocking of bail 241 and the preceding release of latch 173 by cam 56 after which T-lever 158 is freed to return to normalcy. By this structure is permitted the assembling of another line of 40 matrices while awaiting the return of the delivery slide 211. The leftward motion of lever 175 permits the central portion 215 thereof to move away from the depending arm 216 of bell crank 217, whereupon during the cycle of rotation of 45 shaft 48, when side arm 244 of latch 173 is engaged by the apex of cam 56, the offset portion 171 of slide lever 169 is permitted to override the shoulder 172 in response to the urge of spring 161 transmitted through T-lever 158. This 50 causes another arm 162 of lever 158 to shift the link 163 rightwardly as viewed in Fig. 9, effecting the reengagement of clutch elements 167 and 202 for driving shaft 45 when permitted to do so by bail 241 as already described.

55 At a point in the revolution of shaft 48 clutch cam 247 engages the roller 246, Fig. 15, of bell crank 245 moving clutch lever 218 into engagement with its associated driven clutch member 222 to arrest further movement of shaft 48. In 60 this manner, it will be understood that but one cycle of operation is permitted to the elevator shaft 48 and that at the conclusion thereof it is automatically brought to rest under its own control and independently of any of the rest of the 65 unit mechanism. Thus, too, it will be noted that when the elevator operating power shaft 48 is functioning the record reader shaft 45 is arrested and conversely when the record reader mechanism is in operation the elevator power shaft 48 70 is arrested and that under no condition is it possible for both of these shafts to be operating at the same instant. This correlation between the two subordinated driving shafts 45 and 48 functions to assure safety control insofar as each 75 is dependent for its initiation upon the complete

performance of the other in its preceding cycle of operation.

While the invention has been described in detail with respect to a particular application thereof, it will be understood that modifications and variations may be made without departing from the spirit and scope of the invention. It is therefore not intended to be limited to any of the specific structure disclosed but to be permitted a latitude of interpretation in accordance with the 10 terms of the hereunto appended claims.

What is claimed is:

1. In a control mechanism for linecasting and composing machines, a driving source, a driven train, and a control member operated under the 15 joint control of two predetermined conditions for engaging said driving source and said driven train.

2. In a selector mechanism, a record reader including a set of signal sensitive elements, a corresponding set of permutation elements, means to position said permutation elements in accordance with the action of said corresponding signal sensitive elements, a plurality of members individually selectable in accordance with each position of said set of permutation elements, and means to increase the aggregate permutative possibilities of said set of permutation elements without increasing said set of signal sensitive elements including a further permutation element, means for positioning said further permutation element comprising ones of said members for moving said further permutation element to each of its positions, and spring loaded instrumentalities intermediate said ones of said members and said further permutation element whereby the position of said further permutation element may await sequence in a cycle of operation after actuation of any of said ones of said members. 25

3. In a permutation selector the method of increasing the aggregate selective possibilities without increasing the number of signal controlled primary permutation elements which includes providing additional permutation elements, assigning certain of the original selective possibilities to the function of moving the additional permutation elements, and employing spring loaded motive agents in moving the additional elements whereby the actual movement of the additional elements may be permitted to await clearance 30 from obstruction. 40

4. In a permutation selector, a set of permutation elements individually positioned in accordance with components of code signals, a plurality of function members individually selectable in 45 accordance with each position of said set of elements, and a further permutation element positioned by a pair of said function members including spring loaded instrumentality, and means whereby the positioning of said further element 50 is controlled by a signal affecting said pair of said function members but is executed by said instrumentality. 55

5. In an automatic control unit for linecasting machines having composing mechanism and conveying mechanism, a driving train, a driven train for operating said conveying mechanism, signal controlled means for controlling the operative connection between said driving train, said driven train including a control lever centrally engaged 60 to effect said operative connection, control engagement between said conveying mechanism and one end of said lever, and control engagement between said signal controlled means and the other end of said lever whereby the combined 65

75

action of both of said control engagements establish said operative connection.

6. In a composing machine, a plurality of function weights each having several engagement notches, a plurality of manual control levers having single direction operative engagement within certain ones of said notches, and a plurality of automatically operated control levers having single direction operative engagement within certain others of said notches.

7. Control mechanism for plural function apparatus including a set of uniform function members each affording plural engagement accommodations, a set of manually operated engagement levers cooperating with certain of said engagement accommodations, and a set of automatically operated levers cooperating with certain other of said accommodations whereby the cooperation of each of said sets of levers is independent of that of the other of said sets of levers.

8. In a keyboard control system the method of adapting an automatic control unit without affecting the mechanical balance or touch of the manually operated keys which comprises providing one direction engagement between the keys and their associated elements, and providing similar but other engagement between the automatic control unit and the same associated elements.

9. In a selector mechanism, a plurality of function bars to be selected, a set of permutation elements for selecting said bars, signal controlled means for setting certain of said elements, and function bar controlled means for setting other of said elements including a pair of cooperating levers, an engagement piece secured to said other of said elements and disposed between said levers, spring elements mutually connecting said levers, and latching means for each of said levers whereby the movement of said other of said elements is controlled by said function bar controlled means but executed by spring connected levers.

10. In a linecasting and composing machine, a plurality of matrix releasing elements, mechanism responsive to perforations in a tape for controlling the operation of the matrix releasing elements, an elevator into which the matrices are assembled, a cam for moving said elevator, a clutch through which power is communicated to said cam, and means effective for causing the disengagement of said clutch invariably for each cycle of its rotation.

11. In a linecasting and composing machine, a plurality of matrix releasing elements, permutation bars, means operated in response to perforations in a tape for setting said permutation bars, means controlled through the instrumentality of said permutation bars for operating the matrix releasing elements, an elevator, power driven means for operating said elevator, and means effective irrespective of the position of said elevator for invariably discontinuing the driving connection for each cycle of operation.

12. In a linecasting and composing machine, a plurality of matrix releasing elements, permutation bars, mechanism responsive to code perforations in a tape for setting said permutation bars in varying permutations, means controlled by the setting of the permutation bars for operating said matrix releasing elements, an elevator, power actuated means for operating said elevator, a delivery slide, and means controlled jointly by said delivery slide and said permutation bars for rendering said power driven mechanism effective for the operation of said elevator.

13. In a linecasting machine, a conveying

mechanism including a first conveyor and a second conveyor, an automatic control unit including a record reader, a source of operating power for said conveyors, and means under joint control of said second conveyor and said record reader for establishing communication between said source and said first conveyor.

14. The combination of claim 13 including means under control of said communication for automatically disengaging itself predeterminedly.

15. In a linecasting and composing machine, a plurality of matrix releasing elements, a permutation mechanism controlled by signal storage tape for operating said matrix releasing elements, a cam shaft, means on said cam shaft for effecting the step by step advancement of the tape during the continuous rotation thereof, a clutch through which power is communicated to said shaft, an elevator in which the matrices are assembled, and a latch rocked incident the attainment by said elevator of matrix receiving condition for directly releasing said clutch to communicate power to said cam shaft.

16. In a linecasting and composing machine, a plurality of matrix releasing elements, a permutation mechanism controlled by signal storage tape for operating said matrix releasing elements, a cam shaft, means on said cam shaft for effecting the step by step advancement of the tape during the continuous rotation thereof, a clutch through which power is communicated to said shaft, an elevator in which the matrices are assembled, and a latch operated directly by the elevator for controlling the engagement of said clutch.

17. An automatic unit for keyboard control including the combination of a plurality of key-levers to be operated, a plurality of actuators for operating said key-levers spring urged into selected position, a set of permutation bars severally positionable for permitting said actuators to move into selected position individually, a transverse cam for reciprocating said actuators collectively, a mechanism under control of a perforated tape for positioning said bars, and a driving mechanism for imparting timed operative motion to each of said elements from a common mover.

18. In an automatic control unit for operating keyboards, the combination with a plurality of key-levers of a corresponding plurality of selectable actuating members, a set of permutation elements for selectively conditioning said members individually, a set of feelers for sensing perforations in a control form, and a set of transfer levers for receiving a code setting from said feelers and imparting it to said elements.

19. The combination with a composing machine having a keyboard control of an automatic control unit including a plurality of key actuators, special function actuators, a record reader, an actuator selecting mechanism, and a common shaft for imparting operative motion to all of said elements of said unit.

20. In an automatic control unit for linecasting and composing machines, a plurality of actuators, a mechanism for selectively conditioning said actuators individually, a mechanism for operating conditioned ones of said actuators, a constantly rotating driving shaft, and a driven shaft for operating said mechanisms comprising a single shafting, a constantly rotating driven gear loosely mounted on said shafting and in communication with said driving shaft, and a coupling member secured to said shaft permitting

longitudinally slidable movement for effecting driving connection between said gear and said shafting.

21. In a linecasting and composing machine, 5 an automatic control unit including a set of permutation bars having double edged code notch accommodations, a plurality of function members for performing control functions upon said machine individually selectable in accordance with 10 the position of said bars and oppositely disposed in accordance with said double edged accommodations, spring elements for urging said members against said bars, and a cam for cyclically withdrawing said members from said bars. 15 22. In a linecasting and composing machine, an automatic control unit including a plurality of oppositely aligned selectable function members, a set of elements for selecting said members individually, an operating shaft, means on said 20 shaft for cyclically withdrawing said members from said elements, and means on said shaft for operating selected ones of said members.

23. In a linecasting machine, a conveying mechanism including a first conveyor and a second conveyor, an automatic control unit including 25 a record reader, a source of operating power for said conveyors and said record reader, means under joint control of said second conveyor and said record reader upon the predetermined response of said reader for establishing communication between said source and said first conveyor, means under control of said communication for automatically interrupting said communication predeterminedly, means controlled by 30 said record reader for disconnecting said source of power from said record reader upon said predetermined response of said reader, and additional means for reconnecting said source with said record reader.

40 24. In an automatic operating device for a control keyboard, a plurality of keylevers adapted for manual operation, a corresponding plurality of automatic actuators each having an engagement portion disposed to encounter one of 45 said keylevers upon the operation of said actuator and to remain free of engagement upon the manual operation of its associated keylever, and a signal responsive means for individually selecting said actuators.

50 25. In a control unit for automatically and selectively operating a plurality of keylevers adapted for manual operation, a plurality of keylever actuators, a set of notched permutation elements severally positioned to permit said actuators to be operated individually, a corresponding set of feelers intermittently subjected to the impressions of a moving record strip, and a corresponding set of transfer levers severally movable in timed relation to the intermittent movement of said feelers for receiving a record from said feelers and transferring it to said elements.

55 26. In a line composing machine, a matrix releasing mechanism, an automatic mechanism responsive to control signals for selectively operating said releasing mechanism, a common driving source for motivating each of said mechanisms, a driving connection between said source and said automatic mechanism, and means effective to withhold said driving connection until both of two predetermined conditions have been established.

60 27. In a line composing machine, a plurality of manually controllable keylevers, a corresponding plurality of automatically operable actuating elements having individual engagement with

said keylevers respectively by means of portions thereof overlying said keylevers in arrears of their operating path so as to be effective for moving said keylevers when said actuating elements are operated while not affecting the leverage ratio of said keylevers when the latter are operated manually. 5

28. In a line composing machine, a keyboard comprising a plurality of keylevers arranged in rows for manual operation, a corresponding plurality of selectable elements for automatically operating said keylevers alternately and oppositely staggered and disposed below said keylevers, a set of permutation bars between the alternate alignments of said elements severally positionable for individually selecting them, means for moving each selector element towards said bars upon its selection, and means for thereafter moving said selector element to actuate one of said keylevers. 10 15 20

29. An automatic control unit for individually manipulating the keys of a keyboard mechanism including a plurality of actuators corresponding in number to the number of keys to be controlled, engagement portions associated with said actuators and normally disposed adjacent said keylevers in arrears of their operating path, a plurality of selectable elements arranged in alternately staggered and opposite alignments, a set of selector bars intermediate 25 said alignments, signal controlled means for positioning said selector bars to select one of said elements, means for urging a selected element towards said bars, and a common actuator for thereafter moving said selected element to encounter its associated actuator for ultimately operating one of said keys. 30 35

30. In a selector mechanism, a plurality of selectable elements, a set of permutative selector bars, signal controlled means for variously positioning said bars to effect the individual selection of said elements, and a spreader interposed to block the selective response of a selected element for a predetermined interval when said bars are positioned to allow its selective freedom and to permit said response after the transition of a predetermined interval. 40 45

31. In a line composing machine, a manual control keyboard having bayonet pin projections, and an automatic control unit including signal controlled actuating means for said keyboard and bayonet receiving lugs for engaging said pins and thereby supporting said unit. 50

32. The combination with a manual control keyboard of an automatic keylever operating unit, and bayonet connection means for supporting said unit by said keyboard. 55

33. The combination with a manual control keyboard having a supporting base, of a signal controlled operating unit underslung thereof, a supporting structure for said unit, and connections between said structure and said base. 60

34. The combination set forth in claim 33 in which said connections are bayonet joints for facilitating disassembly. 65

35. In a control mechanism for line casting and composing machines, a record reader, an elevator operating mechanism, a driven mechanism for said elevator operating mechanism, a driving unit in operative communication with 70 said driven mechanism, and means including a control member under joint influence of said elevator mechanism and said record reader operative to control the driving relation between said driving unit and said driven mechanism. 75

36. In a selector mechanism, a record reader including a set of signal sensitive elements, a set of permutation elements, means to position said permutation elements in response to said signal sensitive elements, a plurality of members individually selectable in accordance with the positionment of said set of permutation elements, means to increase the aggregate permutative possibilities of said set of permutation elements 5 without increasing said set of signal sensitive elements including an additional permutation element, means for positioning said element comprising a selectable member for moving it to one of its respective positions, and means controlled 10 by said selectable member and operatively associated with said permutation element whereby the movement of said additional permutation element is delayed until a predetermined point in the cycle of operation of the selector mechanism.
- 20 37. In a linecasting and composing machine, a plurality of matrix releasing elements, mechanism responsive to perforations in a tape for determining the operation of the matrix releasing elements, an elevator, power actuated means for 25 operating said elevator, a delivery slide, and means controlled jointly by said delivery slide and said mechanism for rendering said power driven mechanism effective for the operation of said elevator following the operation of said ele- 30 ments.
38. In a linecasting and composing machine, a plurality of matrix releasing elements, a mechanism controlled by signal storage tape for operating said matrix releasing elements, means for effecting a step-by-step advancement of the tape, means through which power is communicated to 35 said tape advancing means, an elevator in which the matrices are assembled, and means operated when the elevator is in a matrix receiving position for directly controlling the application of 40 power to said tape advancing means.
39. In a composing machine, a plurality of matrix release mechanisms each including a time delay element, a constantly rotating actuator for 45 said mechanisms, an automatic control unit for initiating said mechanisms including a plurality of selectable members having one-directional engagement with said mechanisms, a set of permutation elements for selectively conditioning said 50 members individually, and a regularly moving actuator for acting upon said release mechanisms through the medium of said members.
40. In an automatic control mechanism, a continuously rotatable driving source, a driven member 55 to be actuated by said source, a periodically operative organ actuated by said member, a clutch for establishing driving connection between said source and said driven member, and a control means for said clutch comprising a 60 lever movable by two independent components and adapted to influence said clutch by a resultant movement.
41. In an automatically controlled apparatus, a mechanism to be periodically operated, a constant driving source and means for connecting 65 said source to said mechanism periodically and upon the prevalence of two conditions, including a lever, and means for moving said lever under the control of either of said conditions, the resultant movement of both of said last mentioned 70 means being operative to establish said connection.
42. In a linecasting and composing machine, a matrix composing mechanism and an automatic 75 control unit including means responsive to sig-

- nals stored in a record form for correspondingly initiating the performance of said composing mechanism, and a device for acting upon matrices assembled by said composing mechanism, said device being initially responsive to said control unit and including a conditioning means for permitting the response of said device to said control unit only in the event of predetermined consummate operation by said device during its previous performance. 5
43. In a signal responsive device, a set of code bars, a corresponding set of signal responsive elements each related to one of said code bars, means for positioning each code bar in accordance with its related element, an additional code 10 bar, means responsive to a condition of the several of said elements for positioning said additional code bar including a mechanism initiated by said certain condition of said several elements and permitting a variable delay interval in the 15 positioning of said additional code bar.
44. In an automatic control mechanism having a plurality of individually selectable elements capable of performing individual functions, the method of delaying the performance of certain of 20 said functions which comprises the steps of permitting the partial selection of said elements in response to their selecting signals, and thereafter upon the termination of a predetermined time interval permitting the completion of the selec- 25 tion of said elements and their resulting selective operation.
45. In an automatic control device, a power 30 transmitting shaft, an operating shaft, signal controlled means for interrupting the power transmitting shaft and for rendering operative the operating shaft, a member actuated by the operating shaft, means on the operating shaft for partially disabling the power transmitting shaft interrupting means, and means actuated by the 35 member for completing the disablement of the power transmitting shaft interrupting means.
46. In an automatic control device, a power 40 transmitting shaft, an operating shaft, a source of power, a clutch for connecting the power transmitting shaft to the source of power, a clutch throw-out lever, means effectuated from the power transmitting shaft for actuating the clutch throw-out lever and for rendering opera- 45 tive the operating shaft, a member actuated by the operating shaft, means controlled by the clutch throw-out lever operating means for primarily latching the clutch throw-out lever in 50 operated position, means rendered effective at the beginning of the actuation of said member and rendered ineffective at the end of the actuation 55 of said member for secondarily latching said clutch throw-out lever, and means carried by said operating shaft for disabling the primary latching means during the operation of said member. 60
47. In a linecasting and composing machine, a matrix assembling mechanism, a slug casting mechanism, a conveying mechanism operative between said assembling and said casting mechanisms, an automatic control unit including a common driving source, a record reader, means for controlling the operation of said conveying mechanism, and means operable by an action of 65 said conveying mechanism and an action of said record reader for causing the operation of said means and the control of said conveying mechanism.
48. In a linecasting and composing machine, a matrix assembling mechanism, a linecasting 70

mechanism, a conveying mechanism operative between said assembling and linecasting mechanisms, an automatic control unit including a record reader, means for controlling the operation 5 of said conveying mechanism, and a common driving source for said reader and said means,

and means operable by said conveying mechanism and said record reader jointly for causing the operation of said first mentioned means.
